(57) **CLAIM**

The ornamental design for a plant material compaction apparatus, as shown and described.

DESCRIPTION

FIG. 1 is a top front right side isometric view of a plant material compaction apparatus in accordance with the present design;

FIG. 2 is a bottom rear left side isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective in use view thereof.

The broken lines present in the figures illustrating portions of a plant material compaction apparatus are for environmental purposes only and form no part of the claimed design.
